(57) CLAIM

The ornamental design for a CD organizer, as shown and described.

DESCRIPTION

FIG. 1 is a front elevational view of a CD organizer, the opposite side being identical thereto, showing my new design;

FIG. 2 is a top plan view thereof;

FIG. 3 is a right side elevational view thereof;

FIG. 4 is a left side elevational view thereof, and,

FIG. 5 is a bottom plan view thereof.

The broken line showing in FIG. 5 is included for the purpose of illustrating environment and forms no part of the claimed design.
